UNITED STATES PATENT OFFICE

JOHN O. ARCHER, OF SOLOMONSVILLE, ARIZONA

ROAD-GRADING MACHINE

Application filed May 28, 1927. Serial No. 194,969.

This invention relates to new and useful improvements in road grading machines and has among its objects to provide a machine which will function to successfully cut the 5 humps in a road and simultaneously smooth the road surface; to provide a wheeled main frame having a carriage for supporting the road-engaging cutters and smoothing means; to provide means for raising or lowering 10 either or both sides of the carriage and thereby adapt the cutters and smoothing means to the road surface, and to provide cutters which are readily reversible.

With these and other objects in view which 15 will more fully appear, the nature of the invention will be more clearly understood by following the description, the appended claims, and the several views illustrated in the accompanying drawings.

20 In the accompanying drawings which illustrate one form of my invention:

Fig. 1 is a side elevation of a road grading machine constructed in accordance with my invention,

25 Fig. 2 is a top plan view thereof,

Fig. 3 is a rear elevation of the machine, Fig. 4 is a detail sectional view of Fig. 2.

30 Fig. 5 is a detail sectional view showing the guiding means between the wheeled main frame and the carriage,

Fig. 6 is an enlarged elevation showing the means for mounting one of the cutters on the carriage, and

35 Fig. 7 is a perspective view of one of the cutters.

Like reference numerals designate corresponding parts throughout the several figures of the drawings.

Referring to the accompanying drawings in detail, I have illustrated a road grading machine which includes a wheeled main frame A and a carriage B. The main frame A is supported at its front end by wheels 5-5 and at its rear end by traction wheels 6-6. 40 The frame A consists of side bars 7-8, a front bar 9, a rear bar 10, and intermediate braces 11-11. Fixed to the side bar 7 is a pair of upwardly extending front and rear plates 12 and 13, and fixed to the side bar 8 and extending upwardly therefrom is a pair of front

and rear plates 14 and 15. Secured to the upper ends of the plates 12 and 14 is a cross-bar 16, and secured to the upper ends of the rear plates 13 and 15 is a cross-bar 17. Secured to the cross-bars 16 and 17 is a pair of longitudinally extending supporting bars 18 and 19. The cross-bars 16 and 17 and the longitudinal bars 18 and 19 form in effect a supplemental frame carried by the main frame. 55

The carriage B includes a horizontal frame 60 having longitudinal or side bars 20 and 21, and a front end bar 22 and rear end bar 23. Disposed in the front part of the carriage and connecting the side bars 20 and 21 is a plurality of spaced transverse bars 24, 25 and 26. 65

The bars 22 and 24 are connected by a plurality of spaced supporting arms 27; the bars 24 and 25 are connected by a series of spaced supporting arms 28, and the bars 25 and 26 are connected by a series of spaced support- 70

ing arms 29. Detachably and reversibly secured to each of the supporting arms 27, 28 and 29 is a ground-engaging cutter C. Each cutter is formed from a blank of flat or sheet metal having an upper edge 30, a front edge 75

31, a bottom edge 32, and a rear edge 33. The lower forward portion of the cutter or blade is cut-away to form a plurality of cutting teeth 34 and similarly the upper and rear portion of the blade is cut-away to form a plurality of cutting teeth 35. These teeth are 80

disposed in stepped relation and the teeth 34 are disposed in a diagonal line extending downwardly from the front edge 31 to the bottom edge 32. The teeth 35 are also disposed in a diagonal line extending upwardly from the rear edge 33 to the top edge 30. Each cutting blade C is provided with a pair of openings 36 and 37 for receiving an attaching bolt 38 which passes through the associated supporting arm. A second bolt 39 is 85

associated with each cutter C and this bolt is carried by the associated supporting arm and extends above the teeth 35 for engagement thereby so as to prevent any upward 90

swinging movement of said cutter. The cutters C are secured to the carriage B whereby the front cutting teeth 34 are disposed in a plane below the carriage proper. The supporting arms 27 are stepped relative to the 95 100

supporting arms 29. It will be noted that there are five supporting arms 27, six supporting arms 28, and twelve supporting arms 29. It will also be noted that the supporting arms 28 are stepped relative to the supporting arms 27 and 29.

Secured to the side bars 20 and 21 in rear of the cutters C are two intermediate transverse bars 40 and 41. These two bars 40 and 10 41 together with the rear or end bar 23 constitute a road smoothing means. These bars are disposed in a horizontal plane above the teeth 34 of the cutters C and function to smooth the dirt cut by the cutters C.

15. It is desirable to raise or lower the carriage B relative to the main frame A so as to position the cutters C at different elevations relative to the road surface. It is also desirable to provide means for raising or lowering either 20 or both sides of the carriage B so as to position said carriage in a plane relative to the horizontal in accordance with the surface of the road. To this end, I have mounted upon the supplemental frame a pair of aligned operating shafts 42 and 43, said shafts being journaled at their outer ends in supporting posts 44 and 45, and at their inner ends in a common supporting post 46. A hand wheel 47 is fixed to the shaft 42, and a hand wheel 48 is fixed 30 to the shaft 43. A front cable 49 has its rear end fixed to the shaft 42 and its front end fixed to the front end of the right hand side of the carriage B, said cable being trained over an idler 50 journaled on the longitudinally extending arm 18 of the supplemental frame and located at a point directly above the point of connection between the cable 49 and the carriage B. A rear cable 51 has its upper end 35 fixed to the shaft 42 and its lower end fixed to the rear end of the right hand side of the carriage B. Thus by rotating the shaft 42 towards the left, as viewed in Fig. 1, both the cables 49 and 51 will be wound therearound, and consequently the right hand side of the carriage B will be elevated, and if the shaft 42 is turned in the reverse direction the right hand side of the carriage will be lowered. A front cable 52 has one end trained over an idler 53, similar in position to the idler 50, 40 and the extreme front end portion of said cable is connected to the front portion of the lefthand side of the carriage B. A rear cable 54 has one end fixed to the shaft 43 and the lower end fixed to the rear portion of the left hand side of the carriage B. Thus when the shaft 43 is turned towards the left, as viewed in Fig. 1, the left hand side of the carriage B will be elevated. It will be observed that the raising and lowering means as thus described 45 will be dependent relative to each other. In order to support the weight of the carriage B, and thereby relieve the operator from supporting this weight, I have provided the shafts 42 and 43 with ratchet wheels 55 and 56 respectively. Associated with each ratchet

wheel is a locking dog 57 which is normally held in engagement with the wheel by means of a spring 58. A foot control lever 59 is associated with each dog 57 so as to release said dog whenever it is desired to lower the carriage B.

It is also desirable to provide means for guiding the carriage B in a vertical direction whenever said carriage is being raised or lowered, and to this end, I have provided each of the side bars 7 and 8 with front and rear vertically disposed guides 60 and 61, and fixed to the side bars 20 and 21 of the carriage B are front and rear guide pins 62 and 63 which respectively cooperate with the vertical 75 guides 60 and 61.

From the foregoing, it will be observed that I have provided a road grading machine which includes a wheeled main frame and a carriage supported thereon for vertical movements; a plurality of cutter blades mounted on the front part of the carriage; a plurality of smoothing arms mounted on the rear part of the carriage, and means for raising or lowering either or both sides of said carriage 85 whereby the carriage may be angularly adjusted relative to the horizontal to meet different road surface conditions. It will also be observed that the cutters are constructed and supported whereby they may be readily reversed or interchanged whenever the occasion arises.

It is of course to be understood that the details of structure and arrangements of parts may be variously changed and modified without departing from the spirit and scope of my invention.

I claim:

1. In a road grading machine, the combination with a wheeled main frame, of a carriage supported thereon for vertical movements, vertically disposed guides fixed to the main frame adjacent the front and rear ends and on each side thereof, guide pins fixed to the carriage for cooperation with the guides, separate means for raising and lowering each side of said carriage, and a plurality of road-engaging cutters fixed to said carriage.

2. In a road grading machine, the combination with a wheeled main frame, of a carriage supported thereon for vertical movements, means for raising and lowering said carriage comprising a pair of aligned operating shafts supported transversely adjacent the rear end of the main frame, a pair of front and rear cables connecting each shaft with the front and rear ends of the associated side of the frame, idlers journaled on the frame directly above the respective points of connections between the front cables and the carriage, and a plurality of road-engaging cutters fixed to said carriage.

3. In a road grading machine, the combination with a wheeled main frame, of a carriage supported thereon for vertical movements,

means for raising and lowering said carriage comprising a pair of aligned operating shafts supported transversely adjacent the rear end of the main frame, a pair of front and rear cables connecting each shaft with the front and rear ends of the associated side of the frame, idlers journaled on the frame directly above the respective points of connections between the front cables and the carriage, manual means for independently rotating said shafts, a ratchet mechanism for retaining the shaft against movement in any position of adjustment of said carriage, separate foot controlled means associated with each ratchet mechanism, and a plurality of road-engaging cutters fixed to said carriage.

4. In road grading machines, cutters adapted to be drawn over the roads to scarify the said roads, each cutter comprising a metal plate having its lower forward portion cut-away to form a plurality of stepped cutting teeth extending downwardly in a diagonal plane from the front edge of the plate to the bottom edge thereof.

5. In a road grading machine, the combination with a main wheeled frame, of a carriage supported thereon for vertical movements, independent cable connections at each side of the carriage, independent winding devices associated with the cable connections for raising and lowering the respective sides of the carriage independently of each other, a ratchet mechanism for retaining each of the winding devices against movement in any position of adjustment of said carriage, separate foot controlled means associated with each ratchet mechanism, and a plurality of road engaging cutters fixed to said carriage.

6. In road grading machines, cutters adapted to be drawn over the roads to scarify the said roads, each cutter comprising a metal plate having its lower forward portion and its upper rear portion cut-away to form a lower front and an upper rear plurality of stepped cutting teeth, each plurality extending diagonally downwardly from front to rear, and means to reversibly mount the cutters so that either of the upper or lower pluralities of teeth may be presented to the road.

7. In road grading machines, cutters adapted to be drawn over the roads to scarify the said roads, each cutter comprising a metal plate having its lower forward portion and its upper rear portion cut-away to form a lower front and an upper rear plurality of stepped cutting teeth, each plurality extending diagonally downwardly from front to rear, and means to reversibly mount the cutters so that either of the upper or lower pluralities of teeth may be presented to the road, said mounting means comprising a pivot for the forward portion of each tooth and means to abut the rearward portion of each tooth against upward movement about its pivoted mounting.

8. A road scarifying means comprising a frame including front, rear, side and spaced transverse bars, and spaced longitudinal bars joining certain of the transverse bars; and cutters carried by the frame and adapted to be drawn over the roads to scarify the said roads, each cutter comprising a metal plate having its lower forward portion and its upper rear portion cut-away to form a lower front and an upper rear plurality of stepped cutting teeth, each plurality extending diagonally downwardly from front to rear, and means to pivot the advance end of each cutter to a longitudinal bar with a portion thereof extending below the frame to engage the road and with its trailing end constrained against upward movement by an adjacent transverse bar.

9. A road scarifying means comprising a frame including front, rear, side and spaced transverse bars, and spaced longitudinal bars joining certain of the transverse bars, all of said bars being positioned in a common horizontal plane; and cutters carried by the frame and adapted to be drawn over the roads to scarify the said roads, each cutter comprising a metal plate having its lower forward portion and its upper rear portion cut-away to form a lower front and an upper rear plurality of stepped cutting teeth, each plurality extending diagonally downwardly from front to rear, and means to pivot the advance end of each cutter to a longitudinal bar toward the foremost part of the frame with a portion thereof extending below the frame to engage the road and with its trailing end constrained against upward movement by an adjacent transverse bar.

In testimony whereof I hereunto affix my signature.

JOHN O. ARCHER.
